ATTORNEY

UNITED STATES PATENT OFFICE.

JOHN WEST, OF FITHIAN, ILLINOIS.

PISTON-HEAD.

SPECIFICATION forming part of Letters Patent No. 224,258, dated February 3, 1880.

Application filed August 9, 1879.

To all whom it may concern:

Be it known that I, JOHN WEST, of Fithian, in the county of Vermillion and State of Illinois, have invented a new and valuable Improvement in Piston-Heads; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my improved piston-head. Fig. 2 is a central section thereof. Fig. 3 is a plan view of the same with one disk removed, and Figs. 4, 5, and 6 are details.

This invention has relation to improvements in pistons for steam and other engines.

The object of the invention is to prevent leaking from one side of the piston to the other, and thus to attain the full power of the steam or other force used, and to provide easy and economical means whereby ordinary wear and tear may be taken up and remedied as long as the frictional surfaces may last.

The nature of the invention will be fully explained hereinafter, but consists, essentially, of two or more sets of expansible cleft rings arranged the one set within the other and between the two disks of the head, in combination with radial blocks carrying on their outer edges springs bearing against the inner set of rings, and a conical nut screwed upon the end of the piston-rod, whereby, as the packing-rings, which break joints with each other, are worn away the wear may be taken up by screwing up the said nut, thus pressing the movable blocks outward and spreading the said rings against the walls of the cylinder, as will be hereinafter more fully set forth.

In the annexed drawings, the letter A designates the piston-rod, upon which is screwed one of the disks B of the head. The end of this rod projecting through this disk B is threaded.

C indicates metallic blocks formed or cast on the inner face of disk B at a suitable distance apart, and having between them the blocks D, each of which is provided with a spring, b, rigidly secured to it. The exterior

corners of blocks C are rounded off, as seen in Fig. 1, the curves being made with the center of the piston-rod as a center, and being within and concentric to the perimeter of the disk. The blocks C are preferably cast with the 55 said disk, and the blocks D form around the piston-rod an annular recess, e, gradually narrowing as it approaches the said disk B.

E indicates a conical nut that is passed onto the screw-threaded part of the piston-rod with its small end foremost, and is provided on its larger end with a wrench-seat, d, projecting through a central aperture in the other end disk, B', of the head, by means of which it is conveniently manipulated. Disk B' is secured 65 in place by strong screws extending through it into the guide-blocks C, and is of the same diameter as disk B. In the interval between these disks are arranged, in two layers, the packing-rings J J'. The inner layer is composed of a single ring, J, having an oblique cleft, e, and the outer layer generally of two rings, J', whose combined widths are equal to the width of ring J, and fit snugly around the same. The rings J' are also cleft at e', and are so arranged relative to the inside ring, J, that the said clefts e' are broken by the solid part of the inner ring and the cleft e of the inner ring by the solid portion of the outer ones. Being ground absolutely true and the joints 80 of the rings being broken, leakage is not possible when the said rings are properly arranged.

The piston-head thus constructed operates in connection with a cylinder and its attachments, with the rings J' bearing snugly against 85 the interior walls of the cylinder, forming a tight packing. As these rings wear away and the necessary tightness of the steam-joint is wanting, the head of the cylinder is removed, the conical nut E set up, and the blocks D 90 forced outward from each other with their springs b bearing against the inner ring, J. This is consequently expanded, and, acting against the outer rings, J', causes them to be expanded and their perimeters to be forced 95 against the walls of the cylinder, thus restoring the requisite tight joint.

It will be observed that the springs b bear against the inner ring, J, with a yielding pressure, designed to hold the outer rings in con- 100

tact with the cylinder snugly, but not with sufficient force to bind and create undue pressure or friction.

What I claim as new, and desire to secure 5 by Letters Patent, is—

The combination, in a piston having the spaced disks B B', the spaced fixed blocks C between said disks, the piston-rod A, having thread a' , of the expansible blocks D, having 10 springs b, and forming around the rod a conical recess, c, a conical expansion-nut, E, applied upon the rod, and the expansible cleft-

rings J J', arranged between the disks and breaking joints with each other, all constructed and arranged to operate substantially as shown 15 and described.

In testimony that I claim the above I have hereunto subscribed my name in the presence of two witnesses.

JOHN WEST.
